UNITED STATES PATENT OFFICE.

ALLEN P. BOYER, OF GOSHEN, INDIANA.

HOISTING APPARATUS.

No. 878,335.

Specification of Letters Patent.

Patented Feb. 4, 1908.

Application filed September 18, 1907. Serial No. 393,440.

To all whom it may concern:

Be it known that I, ALLEN P. BOYER, a citizen of the United States, residing at the city of Goshen, county of Elkhart, State of Indiana, have invented certain new and useful Improvements in Hoisting Apparatus, of which the following is a specification.

This invention relates to improvements in hoisting apparatus.

10 My improved hoisting apparatus is particularly designed by me for use in carriers, such as hay-carriers and the like, although it is adapted and desirable for use in any relation where it is desired to lock a load in an elevated position.

The main object of this invention is to provide an improved hoisting apparatus adapted to automatically lock a load in any position, that is, at any point in its elevation.

20 Another object is to provide a structure embodying the above advantages which permits the lowering of the load after the same has been hoisted.

Further objects, and objects relating to 25 structural details, will definitely appear from the detailed description to follow.

I accomplish the objects of my invention by the devices and means described in the following specification.

30 The invention is clearly defined and pointed out in the claims.

A structure embodying the features of my invention is clearly illustrated in the accompanying drawing, forming a part of this 35 specification, in which,

Figure 1 is a perspective view of a structure embodying the features of my invention; Fig. 2 is a detail side elevation thereof, the carriage being broken away; Fig. 3 is a 40 detail view with one side of the frame broken away, the clutch member being shown in its engaging position by dotted lines, the pivots for the clutch supporting link and the pulley spindle being shown in section; Fig. 4 is a 45 detail vertical section taken on a line corresponding to line 4—4 of Fig. 3; Fig. 5 is an enlarged detail section taken on a line corresponding to line 5—5 of Fig. 4, of the clutch member and supporting link therefor; 50 and Fig. 6 is an enlarged detail taken on a line corresponding to line 6—6 of Fig. 5, showing the relation of the clutch actuating pawl and the pulley.

In the drawing, the sectional views are 55 taken looking in the direction of the little

arrows at the ends of the section lines, and similar reference characters refer to similar parts throughout the several views.

Referring to the drawing, the structure illustrated is provided with a carriage as 1. 60 The carriage 1 is provided with wheels 2 adapted to travel on a suitable track. The frame is preferably made up of side pieces 3 and a bottom piece 4, suspended and secured to the carriage by means of the bolts 5, the 65 side pieces of the frame being connected by the bolt 6.

The pulley 7 is journaled on a suitable spindle 8 preferably arranged longitudinally of the carriage so that the pulley is transverse thereof, as is illustrated in the drawing. 70 The pulley is provided with laterally-projecting teeth or projections 9 arranged at suitable intervals about the same. A clutch member 10 is pivotally mounted on the upper ends of the links 11 by means of the pivot bolt 12. The links 11 are mounted on the pivots 13 which are preferably arranged in advance of the spindle 8 for the pulley. The inner or gripping face of the clutch member 75 10 is preferably curved to correspond to the pulley and coacts therewith in gripping a rope. The supporting links for the clutch member or clamping jaws 10 are so arranged that, when they are swung downwardly, the 80 clutch member is forced or carried inwardly against the rope on the pulley, clamping the 85 same thereon.

One of the links is slotted at 14 to receive the pin 15 on the clutch member, thereby 90 limiting the pivotal movement of the clutch member on the links. This arrangement allows the clutch member to adjust itself to the rope and avoids the necessity of the accurate fitting and arrangement of the parts. 95 The clutch member is preferably pivoted so that its forward end over-balances the rear end.

On the inner face of one of the links 11 is a rigid pawl or tooth 16 adapted, when the 100 links are swung slightly downward, to be engaged by the teeth 9 on the pulley, so that the rearward movement of the pulley draws the clamping member down into its clamping position; see the dotted lines in Fig. 3. This 105 pawl is preferably V-shaped, its engaging faces being preferably curved. The supporting-links for the clutch member are normally held in their elevated position by the sliding dog 17 having an arm 18 which engages the 110

downwardly-projecting arm 19 on one of the links.

When the links are in their elevated position, the pulley is free to revolve in either direction without acting thereon. When, however, the links are released by the dog 17 they drop downward of their own weight, so that the pawl thereon is in position to be engaged by the teeth on the pulley. The rearward movement of the pulley, as explained, draws the clutch member down onto the rope, thereby clamping the same. On the forward movement of the pulley the teeth on the pulley engage the under side of the pawl passing under the same to lift the clutch free from the rope. The trip dog 17 is arranged in a suitable way 20 provided therefor in the side of the frame. The trip dog is held normally upward by the spring 21 which engages the hook 22 on the dog. This spring is preferably carried by the wheel-like support 23 provided therefor on the side of the frame; see Figs. 1 and 2. In order that the clutch may be automatically actuated by the load, I provide a trip 24, which is adapted to engage the arm 25 on the trip dog. The trip 24 is held normally upward by springs 26. The swivel 27 is connected to the trip member. The hoisting rope 28 is connected to the trip member 24 by means of the swivel, and, after passing through the running pulleys 29, is brought over the pulley 7. The trip member 24 is mounted upon the vertical frame bolts 5 to slide thereon so that it is properly guided. Thus arranged, the greater the load the greater the clamping force of the clutch. The spring 21 is preferably not strong enough to release the clutch member or raise it from its clutching position until the same is released by the slight forward movement of the pulley, which lifts the clutch from the rope, the spring being of sufficient strength to counterbalance the weight of the clutch and its support and hold it in its elevated position. This is an advantage, as it prevents the releasing of the hoisting rope after the load is released, which is of great advantage, particularly in hay-carriers, as the sling or fork is held in its elevated position during the return of the carrier to its hoisting position, where, by a slight pull on the hoisting rope or on the trip rope 30, the clutch is released so that the sling or fork may be readily lowered. It is sometimes desirable to release the clutch so that a load may be relowered. This may be done by the trip rope 30, which is preferably connected to the top of the clutch. A spring 31 is preferably provided for sustaining the weight of the trip rope. By arranging the parts as I have illustrated and described, I provide a device by which the load is automatically locked in any position, the weight of the load serving to actuate the clutch. The load may be lowered as desired. The pulley forms one of the

clutch members, thereby simplifying the construction. The rope is clamped so that the wear thereon is reduced to a minimum.

I have illustrated and described my improved hoisting apparatus in detail in the form preferred by me on account of the structural simplicity and convenience in operation. I am, however, aware that it is capable of considerable variation in structural details without departing from my invention, and I desire to be understood as claiming the same specifically, as illustrated, as well as broadly.

Having thus described my invention, what I claim as new and desire to secure by Letters Patent is:

1. The combination with a frame, of a pulley having teeth thereon; a link having a slot therein, pivoted on said frame, the pivot for said link being arranged in front of the journal for said pulley; a clutch member having a curved engaging face adapted to coact with the pulley in gripping a rope, pivotally mounted on said link; a pin on said clutch member adapted to engage said slot in said link whereby the pivotal movement of said clutch member is limited; a dog adapted to hold said link in its elevated position; a return spring therefor; a downwardly and forwardly-projecting V-shaped fixed pawl or tooth on said link adapted to engage the teeth on said pulley when said link is released by said dog; a hoisting rope; a trip member for said dog to which said rope is connected; and a return spring for said trip member.

2. The combination with a frame, of a pulley having teeth thereon; a link pivoted on said frame, the pivot for said link being arranged in front of the journal for said pulley; a clutch member adapted to coact with the pulley in gripping a rope, pivotally mounted on said link; a dog adapted to hold said link in its elevated position; a return spring therefor; a downwardly and forwardly-projecting V-shaped pawl or tooth on said link adapted to engage the teeth on said pulley when said link is released by said dog; a hoisting rope; a trip member for said dog to which the said rope is connected; and a return spring for said trip member.

3. The combination with a frame, of a pulley having teeth thereon; a link having a slot therein pivoted on said frame, the pivot for said link being arranged in front of the journal for said pulley; a clutch member having a curved engaging face adapted to coact with the pulley in gripping a rope, pivotally mounted on said link; a pin on said clutch member adapted to engage said slot in said link whereby the pivotal movement of said clutch member is limited; a dog adapted to hold said link in its elevated position; a return spring therefor; a pawl on said link adapted to engage the teeth on said

pulley when said link is released by said dog; a hoisting rope; a trip member for said dog to which the said rope is connected; and a return spring for said trip member.

5 4. The combination with a frame, of a pulley having teeth thereon; a link pivoted on said frame, the pivot for said link being arranged in front of the journal for said pulley; a clutch member adapted to coact with the pulley in gripping a rope pivotally mounted on said link; a dog adapted to hold said link in its elevated position; a pawl on said link adapted to engage the teeth on said pulley when said link is released by said dog; a hoisting rope; a trip member for said dog to which the said rope is connected; and a return spring for said trip member.

5. The combination with a frame, of a pulley having teeth thereon; a link having a slot therein pivoted on said frame, the pivot for said link being arranged in front of the journal for said pulley; a clutch member having a curved engaging face adapted to coact with the pulley in gripping a rope, pivotally mounted on said link; a pin on said clutch member adapted to engage said slot in said link whereby the pivotal movement of said clutch member is limited; a dog adapted to hold said link in its elevated position; a downwardly and forwardly-projecting V-shaped fixed pawl or tooth on said link adapted to engage the teeth on said pulley when said link is released by said dog; a hoisting rope; and a trip member for said dog to which the said rope is connected.

6. The combination with a frame, of a pulley having teeth thereon; a link pivoted on said frame, the pivot for said link being arranged in front of the journal for said pulley; a clutch member adapted to coact with the pulley in gripping a rope pivotally mounted on said link; a dog adapted to hold said link in its elevated position; a downwardly and forwardly-projecting V-shaped fixed pawl or tooth on said link adapted to engage the teeth on said pulley when said link is released by said dog; a hoisting rope; and a trip member for said dog to which the said rope is connected.

7. The combination with a frame, of a pulley having teeth thereon; a link having a slot therein pivoted on said frame, the pivot for said link being arranged in front of the journal for said pulley; a clutch member having a curved engaging face adapted to coact with the pulley in gripping a rope, pivotally mounted on said link; a pin on said clutch member adapted to engage said slot in said link whereby the pivotal movement of said clutch member is limited; a dog adapted to hold said link in its elevated position; a pawl on said link adapted to engage the teeth on said pulley when said link is released by said dog; a hoisting rope;

and a trip member for said dog to which the said rope is connected.

8. The combination with a frame, of a pulley having teeth thereon; a link pivoted on said frame, the pivot for said link being arranged in front of the journal for said pulley; a clutch member adapted to coact with the pulley in gripping a rope, pivotally mounted on said link; a dog adapted to hold said link in its elevated position; a pawl on said link adapted to engage the teeth on said pulley when said link is released by said dog; a hoisting rope; and a trip member for said dog to which the said rope is connected.

9. The combination with a frame, of a pulley having teeth thereon; a link having a slot therein pivoted on said frame, the pivot for said link being arranged in front of the journal for said pulley; a clutch member having a curved engaging face adapted to coact with the pulley in gripping a rope, pivotally mounted on said link; a pin on said clutch member adapted to engage said slot in said link whereby the pivotal movement of said clutch member is limited; a downwardly and forwardly-projecting V-shaped fixed pawl or tooth on said link adapted to engage the teeth on said pulley when said link is released by said dog; and a dog adapted to hold said link in its elevated position arranged to be tripped by the weight of the load on the hoisting rope.

10. The combination with a frame, of a pulley having teeth thereon; a link pivoted on said frame, the pivot for said link being arranged in front of the journal for said pulley; a clutch member having a curved engaging face adapted to coact with the pulley in gripping a rope pivotally mounted on said link; a downwardly and forwardly-projecting V-shaped fixed pawl or tooth on said link adapted to engage the teeth on said pulley when said link is released by said dog; and a dog adapted to hold said link in its elevated position arranged to be tripped by the weight of the load on the hoisting rope.

11. The combination with a frame, of a pulley having teeth thereon; a link having a slot therein pivoted on said frame, the pivot for said link being arranged in front of the journal for said pulley; a clutch member adapted to coact with the pulley in gripping a rope, pivotally mounted on said link; a pin on said clutch member adapted to engage said slot in said link whereby the pivotal movement of said clutch member is limited; a downwardly and forwardly-projecting V-shaped fixed pawl or tooth on said link adapted to engage the teeth on said pulley when said link is released by said dog; and a dog adapted to hold said link in its elevated position arranged to be tripped by the weight of the load on the hoisting rope.

12. The combination with a frame, of a pulley having teeth thereon; a link pivoted

on said frame, the pivot for said link being arranged in front of the journal for said pulley; a clutch member adapted to coact with the pulley in gripping a rope, pivotally mounted on said link; a downwardly and forwardly-projecting V-shaped fixed pawl or tooth on said link adapted to engage the teeth on said pulley when said link is released by said dog; and a dog adapted to hold said link in its elevated position arranged to be tripped by the weight of the load on the hoisting rope.

13. The combination with a frame, of a pulley having teeth thereon; a link having a slot therein pivoted on said frame; the pivot for said link being arranged in front of the journal for said pulley; a clutch member having a curved engaging face adapted to coact with the pulley in gripping a rope, pivotally mounted on said link; a pin on said clutch member adapted to engage said slot in said link whereby the pivotal movement of said clutch member is limited; a pawl on said link adapted to engage the teeth on said pulley when said link is released by said dog; and a dog adapted to hold said link in its elevated position arranged to be tripped by the weight of the load on the hoisting rope.

14. The combination with a frame, of a pulley having teeth thereon; a link pivoted on said frame, the pivot for said link being arranged in front of the journal for said pulley; a clutch member having a curved engaging face adapted to coact with the pulley in gripping a rope pivotally mounted on said link; a pawl on said link adapted to engage the teeth on said pulley when said link is released; and a dog adapted to hold said link in its elevated position arranged to be tripped by the weight of the load on the hoisting rope.

15. The combination with a frame of a pulley having teeth thereon; a link having a slot therein pivoted on said frame, the pivot for said link being arranged in front of the journal for said pulley; a clutch member adapted to coact with the pulley in gripping a rope pivotally mounted on said link; a pin on said clutch member adapted to engage said slot in said link whereby the pivotal movement of said clutch member is limited; a pawl on said link adapted to engage the teeth on said pulley when said link is released; and a dog adapted to hold said link in its elevated position arranged to be tripped by the weight of the load on the hoisting rope.

16. The combination with a frame, of a pulley having teeth thereon; a link pivoted on said frame, the pivot for said link being arranged in front of the journal for said pulley; a clutch member adapted to coact with the pulley in gripping of a rope, pivotally mounted on said link; a pawl on said link adapted to engage the teeth on said pulley when said link is released; and a dog adapted

to hold said link in its elevated position arranged to be tripped by the weight of the load on the hoisting rope.

17. The combination with a frame, of a pulley having teeth thereon; a link pivoted on said frame, the pivot for said link being arranged in front of the journal for said pulley; a clutch member adapted to coact with the pulley in gripping a rope, mounted on said link; a downwardly and forwardly-projecting V-shaped fixed pawl or tooth on said link adapted to engage the teeth on said pulley when said link is released; and a dog adapted to hold said link in its elevated position arranged to be tripped by the weight of the load on the hoisting rope.

18. The combination with a frame, of a pulley having teeth thereon; a link having a slot therein pivoted on said frame, the pivot for said link being arranged in front of the journal for said pulley; a clutch member adapted to coact with the pulley in gripping a rope, mounted on said link; a pin on said clutch member adapted to engage said slot in said link whereby the pivotal movement of said clutch member is limited; a pawl on said link adapted to engage the teeth on said pulley when said link is released; and a dog adapted to hold said link in its elevated position arranged to be tripped by the weight of the load on the hoisting rope.

19. The combination with a frame, of a pulley having teeth thereon; a link pivoted on said frame; a clutch adapted to coact with the pulley in gripping a rope, pivotally mounted on said link; a dog adapted to hold said link normally upward; a trip for said dog adapted to be actuated by the weight of the load; and a forwardly-projecting V-shaped fixed pawl or tooth on said link adapted to engage the teeth on said pulley when the link is released by said dog whereby said clutch member is drawn into its clamping position by the rearward revolution of the pulley and lifted out of its clamping position by the forward revolution of the pulley.

20. The combination with a frame, of a pulley having teeth thereon; a link pivoted on said frame; a clutch adapted to coact with the pulley in gripping a rope pivotally mounted on said link; a dog adapted to hold said link normally upward; a trip for said dog adapted to be actuated by the weight of the load; and a pawl on said link adapted to engage the teeth on said pulley when the link is released by said dog whereby said clutch member is drawn into its clamping position by the rearward revolution of the pulley and lifted out of its clamping position by the forward revolution of the pulley.

21. The combination with a frame, of a pulley having teeth thereon; a link pivoted on said frame; a clutch adapted to coact with the pulley in gripping a rope, mounted on said link; a dog adapted to hold said link

normally upward; a trip for said dog adapted to be actuated by the weight of the load; and a forwardly-projecting V-shaped fixed pawl or tooth on said link adapted to engage the teeth on said pulley when the link is released by said dog whereby said clutch member is drawn into its clamping position by the rearward revolution of the pulley and lifted out of its clamping position by the forward revolution of the pulley.

22. The combination with a frame, of a pulley having teeth thereon; a link pivoted on said frame; a clutch adapted to coact with the pulley in gripping a rope, mounted on said link; a dog adapted to hold said link normally upward; a trip for said dog adapted to be actuated by the weight of the load; and a pawl on said link adapted to engage the teeth on said pulley when the link is released by said dog whereby said clutch member is drawn into its clamping position by the rearward revolution of the pulley and lifted out of its clamping position by the forward revolution of the pulley.

23. The combination with a frame, of a pulley having teeth thereon; a link pivoted on said frame; a clutch adapted to coact with the pulley in gripping a rope, pivotally mounted on said link; a dog adapted to hold said link normally upward; a trip for said dog; and a forwardly-projecting V-shaped fixed pawl or tooth on said link adapted to engage the teeth on said pulley when the link is released by said dog whereby said clutch member is drawn into its clamping position by the rearward revolution of the pulley and lifted out of its clamping position by the forward revolution of the pulley.

24. The combination with a frame, of a pulley having teeth thereon; a link pivoted on said frame; a clutch adapted to coact with the pulley in gripping a rope, pivotally mounted on said link; a dog adapted to hold said link normally upward; a trip for said dog; and a pawl on said link adapted to engage the teeth on said pulley when the link is released by said dog whereby said clutch member is drawn into its clamping position by the rearward revolution of the pulley and lifted out of its clamping position by the forward revolution of the pulley.

25. The combination with a frame, of a pulley having teeth thereon; a link pivoted on said frame; a clutch adapted to coact with the pulley in gripping a rope, mounted on said link; a dog adapted to hold said link normally upward; a trip for said dog; and a forwardly-projecting V-shaped fixed pawl or tooth on said link adapted to engage the teeth on said pulley when the link is released by said dog whereby said clutch member is drawn into its clamping position by the rearward revolution of the pulley and lifted out of its clamping position by the forward revolution of the pulley.

26. The combination with a frame, of a pulley having teeth thereon; a link pivoted on said frame; a clutch adapted to coact with the pulley in gripping a rope, mounted on said link; a dog adapted to hold said link normally upward; a trip for said dog; and a pawl on said link adapted to engage the teeth on said pulley when the link is released by said dog whereby said clutch member is drawn into its clamping position by the rearward revolution of the pulley and lifted out of its clamping position by the forward revolution of the pulley.

27. The combination with a frame, of a pulley having teeth thereon; a movably-supported clutch member arranged to coact with the pulley in clamping a rope; a pawl adapted to engage the teeth of said pulley; a dog adapted to hold said pawl out of its engaging position; a trip for said dog adapted to be actuated by the load, said pawl being arranged to engage the teeth of said pulley when released by said dog, whereby on the rearward movement of the pulley the clutch member is drawn into its clamping position and moved therefrom by the forward movement of the pulley and a spring arranged to normally hold the pawl out of its engaging position, the tension of the return spring being insufficient to release said clamping member when clamping a rope.

28. The combination with a frame, of a pulley having teeth thereon; a movable clutch member arranged to coact with the pulley in clamping a rope; means for holding said clutch member yieldingly out of its engaging position; a pawl adapted to engage the teeth of said pulley; means actuated by the load for bringing said pawl into engagement with the teeth of the said pulley, said pawl being adapted on the rearward movement of the pulley to draw the said clutch member into its clamping position, and on the forward movement of the pulley to move said clutch member from its clamping position when the load is discharged.

29. The combination with a frame of a pulley; a movably supported clutch member arranged to coact with the pulley in clamping a rope; means for holding said clutch member yieldingly out of its engaging position; means for connecting said clutch member with said pulley arranged so that on the rearward movement of the pulley, the clutch member is drawn into its clamping position, and on the forward movement of the pulley is moved therefrom, said means for connecting said clutch member to said pulley being brought into engaging position by the load and being automatically moved from its engaging position when the load is released.

30. The combination with a frame, of a pulley having teeth thereon; a link pivoted on said frame; a clutch adapted to coact with

the pulley in gripping a rope, mounted on said link; a dog adapted to hold said link normally upward; a trip for said dog adapted to be actuated by the weight of the load; a pawl on said link adapted to engage the teeth on said pulley when the link is released by said dog whereby said clutch member is drawn into its clamping position by the rearward revolution of the pulley and lifted out of its clamping position by the forward revolution of the pulley; and a trip rope connected to said clutch member.

31. The combination with a frame, of a pulley having teeth thereon; a link pivoted on said frame; a clutch adapted to coact with the pulley in gripping a rope, pivotally mounted on said link; a dog adapted to hold said link normally upward; a trip for said dog; a forwardly-projecting V-shaped fixed pawl or tooth on said link adapted to engage the teeth on said pulley when the link is released by said dog, whereby said clutch member is drawn into its clamping position by the rearward revolution of the pulley and lifted out of its clamping position by the forward revolution of the pulley; and a trip rope connected to said clutch member.

32. The combination with a frame, of a pulley having teeth thereon; a link pivoted on said frame; a clutch adapted to coact with the pulley in gripping a rope, pivotally mounted on said link; a dog adapted to hold said link normally upward; a trip for said dog; a pawl on said link adapted to engage the teeth on said pulley when the link is released by said dog whereby said clutch member is drawn into its clamping position by the rearward revolution of the pulley and lifted out of its clamping position by the forward revolution of the pulley; and a trip rope connected to said clutch member.

33. The combination with a frame, of a pulley having teeth thereon; a link pivoted on said frame; a clutch adapted to coact with the pulley in gripping a rope, mounted on said link; a dog adapted to hold said link normally upward; a trip for said dog; a forwardly-projecting V-shaped fixed pawl or tooth on said link adapted to engage the teeth on said pulley when the link is released by said dog whereby said clutch member is drawn into its clamping position by the rearward revolution of the pulley and lifted out of its clamping position by the forward revolution of the pulley; and a trip rope connected to said clutch member.

34. The combination with a frame, of a pulley having teeth thereon; a link pivoted on said frame; a clutch adapted to coact with the pulley in gripping a rope, mounted on said link; a dog adapted to hold said link normally upward; a trip for said dog; a pawl on said link adapted to engage the teeth on said pulley when the link is released by said dog whereby said clutch member is

drawn into its clamping position by the rearward revolution of the pulley and lifted out of its clamping position by the forward revolution of the pulley; and a trip rope connected to said clutch member.

35. The combination with a frame, of a pulley having teeth thereon; a movably-supported clutch member arranged to coact with the pulley in clamping a rope; a pawl adapted to engage the teeth of said pulley; a dog adapted to hold said pawl out of its engaging position; a trip for said dog adapted to be actuated by the load, said pawl being arranged to engage the teeth of said pulley when released by said dog, whereby on the rearward movement of the pulley the clutch member is drawn into its clamping position and moved therefrom by the forward movement of the pulley and a spring arranged to normally hold the pawl out of its engaging position, the tension of the return spring being insufficient to release said clamping member when clamping a rope; and a trip rope connected to said clutch member.

36. The combination with a frame of a pulley; a movably supported clutch member arranged to coact with the pulley in clamping a rope; means for holding said clutch member yieldingly out of its engaging position; means for connecting said clutch member with said pulley arranged so that on the rearward movement of the pulley, the clutch member is drawn into its clamping position, and on the forward movement of the pulley is moved therefrom, said means for connecting said clutch member to said pulley being brought into engaging position by the load and being automatically moved from its engaging position when the load is released, and a trip rope connected to said clutch member.

37. The combination with a frame, of a pulley having teeth thereon; a movable clutch member arranged to coact with the pulley in clamping a rope; means for holding said clutch member yieldingly out of its engaging position; a pawl adapted to engage the teeth of said pulley; means actuated by the load for bringing said pawl into engagement with the teeth of said pulley, said pawl being adapted on the rearward movement of the pulley to draw the said clutch member into its clamping position, and on the forward movement of the pulley to move said clutch member from its clamping position when the load is discharged; and a trip rope connected to said clutch member.

In witness whereof, I have hereunto set my hand and seal in the presence of two witnesses.

ALLEN P. BOYER. [L. s.]
